UNITED STATES PATENT OFFICE.

HERMAN HAEFLIGER, OF NORTH PLATTE, NEBRASKA.

BALANCE-PIVOT STRAIGHTENER.

1,347,155.

Specification of Letters Patent. Patented July 20, 1920.

Application filed June 6, 1919. Serial No. 302,359.

To all whom it may concern:

Be it known that I, HERMAN HAEFLIGER, a citizen of Switzerland, residing at North Platte, county of Lincoln, and State of Nebraska, have invented certain new and useful Improvements in Balance-Pivot Straighteners; and I do declare the following to be a full, clear, and exact description of the invention, such as will enable others skilled in the art to which it appertains to make and use the same, reference being had to the accompanying drawings, and to the characters of reference marked thereon, which form a part of this specification.

15 This invention relates to object-holders to be employed for microscopes for the use of watchmakers.

The object of the invention is to provide a device for holding an object in the field of view of the microscope.

Briefly, the invention comprises a microscope and base, a yoke member being mounted on the base and adjustably holding opposed supporting arms, which are provided at their adjacent extremities with apertures to receive the ends of a balance-staff, one of these members being also equipped with adjustable means to straighten a pivot of the staff.

30 In the drawings:

Figure 1 is a perspective showing the device as used on a microscope.

Fig. 2 is a fragmentary perspective on an enlarged scale, showing roughly a balance wheel in position in the holder, a portion of the balance wheel being broken away.

In detail, the microscope 5 is mounted on a base 6, having supports 7 and 8, on one of which a yoke 9 is positioned. The arms 40 of the yoke are split at 10 as shown, and equipped with adjustable nuts 12 for the purpose of clamping in the arms opposed supporting members 14 and 15. The arm 15 is provided with an axial aperture 16 to receive the pivot A of the balance wheel B, and a transverse sight-opening 17 communicates with the aperture 16. The arm 14 is provided with a lateral U-shaped cut 20, into the bottom of which is threaded a screw 21, whose end 22 is shaped to engage the pivot C of the balance staff, which projects through the upstanding end-piece 23, an aperture 24 being provided in the end piece 23 for the reception of the pivot, the aperture 24 being alined with the axis of the arm 14. In operation, the balance wheel and its staff are mounted, as shown in Fig. 2, and

adjusted with respect to the microscope to be in the field of vision. When the pivot C is bent, the balance wheel is rotated to a 60 position to direct the bent pivot toward the face 22 of screw 21, which is brought into engagement therewith by turning to straighten the same in one plane, and this operation is repeated to eventually 65 straighten the pivot C to be absolutely true with respect to the axis of the balance staff. The opening 17 enables the observer to determine the condition of the pivot A, and the U-shaped cut 20 enables him to carefully observe the effect of his work upon the pivot C.

I claim:

1. In combination, a microscope having a base, and an object holder positioned to present an object in the field of the microscope, said holder comprising two opposing supporting members apertured to receive the pivots of a balance staff, one of said members being cut out to expose the protruding 80 pivot.

2. In combination, a microscope having a base, an object holder positioned to present an object in the field of the microscope, said holder comprising two opposing supporting 85 members apertured to receive the pivots of a balance staff, one of said members being cut out to expose the protruding pivot, and a screw projecting into said cut-out portion to adjustably engage said pivot for straightening purposes.

3. An object-holder comprising two opposing members apertured to receive the pivots of a balance staff, one of said members having a cut in the side thereof communicating with the aperture therein, and into which one pivot is adapted to project, and an adjustable means mounted in the member and projecting into said cut to adjustably engage said pivot.

4. An object-holder comprising two opposing members apertured to receive the pivots of a balance staff, one of said members having a cut in the side thereof communicating with the aperture therein and into which one pivot is adapted to project, and an adjustable screw mounted in the member and projecting into said cut to adjustably engage said pivot, and the other member having a sight opening in the side 110 thereof communicating with its aperture.

In testimony whereof I affix my signature.

HERMAN HAEFLIGER.
